HEATING SYSTEM

Luis Diaz Gonzalez, Seville, Spain

Application December 4, 1948; Serial No. 63,553
In Spain April 7, 1948

1 Claim. (Cl. 263—19)

1. The present invention relates to heating systems and, more particularly, to systems of the type wherein a heat-carrying fluid, for example air, is circulated through the space or body to be heated after having previously been brought to an elevated temperature in a furnace or heating unit.

An object of the present invention is to provide a system of the character described in which means are provided for initially heating the heat-carrying medium, such as air, to very high temperatures, e. g. of the order of 500° C.

Fundamentally, an indirect heating system of the type described may operate in one of two manners: Either the heated fluid is circulated through a conduit system to give off its heat to its surroundings by contact and/or radiation, or the fluid (preferably air) is directly introduced into the atmosphere of the room which is to be heated. In the latter case, care must be taken that the fluid (air) be free from contamination by the flue gases of the furnace in which it had been heated, no such precautions being necessary in the former case.

It is another object of the invention to provide, in a heating system, means for utilizing a heated fluid (preferably air) in either of the two manners described.

It is a further object of the invention to provide, in a system wherein a heated fluid is circulated through conduits, means for optionally admixing the hot flue gases with said fluid, whereby the efficiency of the system and the amount of heat obtainable therefrom will be increased.

Still another object of the invention is to provide a heating unit having means for enabling greatest possible heating contact between a source of heat and a fluid to be heated to be obtained.

The above and further objects of the invention will become apparent from the following description of a preferred embodiment, reference being had to the accompanying drawing in which:

Fig. 1 is a front elevational view, partly in section, of a heating unit according to the invention; and

Fig. 2 is a side elevation of the unit shown in Fig. 1, part of a side wall being broken away to expose the underlying structure of the heating unit.

Referring to the drawing in detail, the heating unit comprises a furnace having a front wall 1, a rear wall 2, side walls 3 and 4, a top wall 5 and

2. a bottom wall 6, these walls constituting a hermetically sealed housing which encloses an outer chamber or heating space 16 and an inner chamber or firebox 7. The firebox or combustion chamber 7 is divided into an upper and a lower compartment by a sliding grate 8, the upper compartment being traversed by a set of tubes 9, arranged in layers or tiers, interconnecting the left-hand and the right-hand side of the outer chamber 16 as viewed in Fig. 1. These tubes may be made of metal or any other suitable material capable of being brought to red heat, and by their shape present a large heating surface for the utilization of the heat produced in the interior of the furnace. Accordingly, the volume of heat which can be transferred to a fluid passing through these tubes, in a manner subsequently to be described, will be very large.

20 A flue pipe or chimney is provided at or near the top of the furnace body, to allow for the escape of combustion gases and smoke when the same are not utilized in the heating system itself, as presently described. For this purpose the chimney 10 communicates with the combustion chamber 7 by means of two curved conduits or tubes 17 whose ends 18 open into the chamber 7 below the grate 8. The tubes 17 pass through the outer chamber 16 where the gases passing through these tubes further contribute to the heating of the heat-carrying fluid.

25 The chimney pipe 10 further communicates with a conduit or tube 12 which leads to a collector 13 from which heated air, entering through an opening or port 19 in the wall 3, may pass into a blower chamber 14 housing a blower (not shown) which is driven from a motor 15 provided with a flywheel 14a.

30 The flue pipe 10 is provided with a valve or damper 11 whereby the passage of the flue gases through this pipe may be regulated or entirely shut off. Similarly, the tube 12 is provided with a valve or shutter 12a permitting this tube to be selectively blocked with respect to any gases coming from the flue pipe 10.

35 The front wall 1 of the furnace is further provided with a pair of tightly closing hatches 20, affording admittance to the chamber 16 for purposes of cleaning, adjustment or repair, and with a door 21 leading to the combustion chamber 7.

40 A thermometer 22 is provided on the top part of the collector chamber 13 to allow temperature measurements to be taken at a location where the temperature of the heat-carrying fluid will 45 be the highest.

In operation, it will be understood that pure, uncontaminated air may be fed into the collector 13 by shutting off the connecting tube 12 between this chamber and the chimney, at the same time opening the damper 11 to provide an escape path for the flue gases. On the other hand, it is equally feasible to admix the hot combustion gases with the air entering through the port 19, for which purpose it is merely necessary to open the shutter 12a and to throttle the passage through the flue pipe by means of the valve 11.

I have found that, with a heating unit of the type just described, air temperatures as high as 500° C. could be obtained.

While the invention has been described with reference to a single, preferred embodiment, it is to be understood that the same is susceptible to numerous modifications and adaptations without departing from the spirit and scope of the invention as defined in the objects and in the appended claim.

I claim:

A furnace comprising a combustion chamber, a heating space at least partially surrounding said chamber, an inlet port connecting said

space with the atmosphere, distributor means communicating with said space, forced draft means in said distributor means, a flue pipe communicating with said chamber, and conduit means connecting said flue pipe with said distributor means, valve means in said flue pipe for throttling the escape of gases therethrough and other valve means in said conduit means disconnecting said distributor means from said flue pipe, a grate dividing said chamber into two compartments, said tubes being disposed in the compartment above the grate, at least one tube connecting said flue pipe with said chamber, said tube extending within said space as an additional heating surface.
